UNITED STATES PATENT OFFICE

2,441,746

RAINCOAT CONSTRUCTION

Egon Bernath, New York, N. Y.

Application April 24, 1945, Serial No. 590,016

1 Claim. (Cl. 2-87)

1

This invention relates to garments. It is particularly directed to outer water-repellent garments such as raincoats and the like articles of clothing.

Difficulty with raincoats as heretofore constructed has been due to the fact that when the garment is worn in the rain, water has a tendency to penetrate at the shoulders on which the raindrops beat down directly. It is, therefore, an object of this invention to provide a garment of the character described having improved water-repellent or waterproofing protection at the shoulders of the garment.

Another object of this invention is to provide in a garment of the character described, shoulder portions which extend outwardly beyond the arm sleeves forming means for guiding water from the shoulders out beyond the arm sleeves and protecting the upper portions of said arm sleeves from contact with the rain.

A still further object of the present invention is to provide a strong, durable and lightweight garment of the character described which shall be inexpensive to manufacture, attractive in appearance, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown various possible illustrative embodiments of this invention:

Fig. 1 is a front elevational view of a garment embodying the invention.

Fig. 2 is a partial perspective view through part of the shoulder portion of the garment.

Fig. 3 is a partial end view of the garment at the shoulder thereof.

Fig. 4 is a cross-sectional view taken on line 4-4 of Fig. 3.

Referring now in detail to the drawing, 10 designates a garment embodying the invention. The same comprises a body 11 provided with arm-sleeves 12. The garment is provided with a lining 14 as shown in Fig. 4 of the drawing. The body of the garment may be made of taffeta or other textile material which has been treated to repel water. The sleeves 12 are stitched to the body and likewise made of the same material.

2

With ordinary garments, water has a tendency to penetrate at the shoulders because the rain beats down directly thereon. In the garment 10 embodying the invention, the body 11 has arm-holes 16 to which the sleeves are stitched. It will thus be noted that the sleeves 12 are stitched as at 12a to the body 11 at the armholes.

Stitched to the body 11 is a shoulder protector 20 embodying the invention. The protector 20 is formed of an under layer 21 of waterproof gabardine or the like textile cloth, and an outer layer 22 of water repellent taffeta or other textile material treated to repel water. The superimposed layers 21, 22 may be quilted together by cross-stitching 23. This material may also be gathered to give a rippy appearance. Protector 20 is stitched inwardly of its ends to the arm sleeves by stitching 24, and it is stitched at the front and back, to the body 11 by lines of stitching 25. The shoulder protector may extend to the longitudinal or split edges 27 of the body as shown in Fig. 1 of the drawing. Said protector thus overlies the shoulder portion 15 of the garment and the front and rear portions adjacent the shoulder.

As shown in Figs. 1 and 4 of the drawing, the protector 20 extends beyond the line of stitching 24, so as to overlie the upper portions of the arm sleeves 12 as shown at 30. The portion 30 of the protector 20 extends in a continuous line so as to be spaced from the sleeve 12 beyond the line of stitching 24. The extension 30 thus forms a sort of shed to carry water coming down the shoulders beyond the armsleeves.

Protector 20 forms an integral part of the garment, but adds protection against penetration of rain at the shoulders of the garment. The garment remains light in weight, as very little weight is added thereto. The garment may be provided with a collar 32 which may be stitched to the protector 20 and made of the same double layered material 21, 22.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

55 Having thus described my invention, what I

claim as new and desire to secure by Letters Patent is:

A garment of the character described comprising a body and sleeves made of taffeta treated with water repellent material, sleeves stitched to the body, and an integral shoulder protector permanently stitched completely around its perimeter to the body and sleeves and overlying the shoulder portion of the body, said shoulder protector having portions extending beyond the seams which attach the sleeves to the body, said shoulder protector comprising an outer layer of water repellent textile material similar to the material of which the body and sleeves are made, and an underlayer of waterproof textile mate-¹⁵rial, said layers being cross-stitched together and gathered to give a quilted rippling appearance.
